Primary Examiner — Karen E Eldridge Powers(74) *Attorney, Agent, or Firm* — McAndrews, Held & Malloy, Ltd.(57) **CLAIM**

The ornamental design for a gusset with cloud shape, substantially as shown and described.

DESCRIPTION

FIG. 1 is a top rear perspective view of a gusset with cloud shape of the present invention, as it may be used in an undergarment (the broken lines shown on the gusset with cloud shape and on the undergarment represent unclaimed features);

FIG. 2 is a plan enlarged view of the claimed gusset with cloud shape;

FIG. 3 is a front elevational enlarged view of the claimed gusset with cloud shape;

FIG. 4 is a rear elevational enlarged view of the claimed gusset with cloud shape; and,

FIG. 5 is a right side elevational enlarged view of the claimed gusset with cloud shape (the left side elevational enlarged view is a mirror image thereof).

The broken lines shown on the gusset are unclaimed features. The lower body garment shown in broken lines represents environmental subject matter that forms no part of the claimed design.
